UNITED STATES PATENT OFFICE.

PETER KREBITZ, OF MUNICH, GERMANY, ASSIGNOR TO KREBITZ PROCESS COMPANY OF AMERICA, OF AURORA, ILLINOIS, A CORPORATION OF ILLINOIS.

APPARATUS FOR THE MANUFACTURE OF SOAP.

1,126,787.

Specification of Letters Patent.

Patented Feb. 2, 1915.

Application filed November 14, 1913. Serial No. 301,028.

To all whom it may concern:

Be it known that I, PETER KREBITZ, a subject of the Emperor of Germany, residing at Munich, in Bavaria, Empire of Germany, have invented certain new and useful Improvements in Apparatus for the Manufacture of Soap, of which the following is a specification.

My invention relates more particularly to apparatus for carrying out the process described in United States Letters Patent No. 858,295 granted to me June 25, 1907. This process stated in general terms consists in adding the oleaginous or fatty matter to be made into soap to a lime emulsion and after heating the same to boiling point permitting the mixture to react without further applied heating but under the heat of its reaction to form a mass of insoluble lime soap impregnated with glycerin. The glycerin is then removed by washing and the insoluble lime soap converted to soluble soap by the addition of carbonate of soda or potash with or without the addition of salt. For a more detailed description of the process reference may be made to the patent to which reference has been made above. The apparatus which forms the subject matter of the present application is particularly well adapted for carrying out this process though as will appear from a reading of the following specification it is also available for many other similar processes with or without modifications such as will suggest themselves to those skilled in this art. The specific illustration and description of a suitable embodiment of the invention is for the purpose of exemplification only, it being understood that the scope of the invention is defined in the following claims in which I have endeavored to distinguish it from the prior art so far as known to me without however abandoning or relinquishing any part thereof.

In the accompanying drawings, Figure 1 is a side elevation partly in section of my complete apparatus, parts being omitted for the sake of clearness; Fig. 2 a section on the line 2—2 of Fig. 1 but somewhat enlarged and some of the parts being shown in section; Fig. 3 an elevation partly in section at right angles to Fig. 2 on a still larger scale; Fig. 4 a plan of that portion of the apparatus shown in Figs. 2 and 3 on the same scale as Fig. 2; Fig. 5 an end elevation

partly in section of the tank forming a part of the apparatus shown in Figs. 2, 3 and 4; Fig. 6 a fragmentary detail of the tank and Fig. 7 a horizontal section on the line 7—7 of Fig. 5.

Each part is referred to by the same reference character throughout the several views.

Referring now to Fig. 1, a mixer A is shown at the left of the figure and at a sufficient elevation to provide for the gravity transfer of the material therefrom to the reaction tank B. Within the tank A is provided a rotary stirrer 8 having a pulley 9 thereon for rotating the same and provided with a series of arms 10 each hollow and perforated as shown for the introduction of steam into the mixer which is supplied to the hollow shaft 8 from some suitable boiler through the supply pipe 11. The emulsion of lime in water of about the consistency of milk or cream is introduced into this mixer with the oleaginous or fatty material and the whole mixed together by rotating the shaft and at the same time heated to the boiling point by the introduction of steam preferably superheated for the purpose. After the intermixture of the ingredients has become sufficiently intimate and the temperature raised to the boiling point the mixture is drawn off through a pipe 12 controlled by a stop cock 13 into the reaction tank B. Here the reaction between the fatty matter and the lime is completed without the application of further heat, the process requiring several hours and the product consisting of a solid mass of insoluble lime soap of open porous texture impregnated with glycerin in comparatively concentrated solution. Other bases such as zinc, baryta, etc., forming insoluble soaps may, if desired, be substituted for lime but the latter is preferred.

In order to readily and completely remove the product from the reaction tank when the reaction is completed I form the tank with an end which may be swung open and provide an excavating apparatus of the character shown more particularly in Figs. 2 to 7 inclusive, adapted to be carried into and along the tank. The end of the tank which may be made of sheet metal is provided with a heavy reinforcing angle iron 14 (see Figs. 5, 6 and 7) which may be of cast metal and riveted to the body of the tank, the out-

wardly extending flange 15 thereof being notched at intervals as at 16 for a purpose which will presently appear. The angle iron is formed with pairs of lugs 17 in registry with the notches in the flange between which lugs are pivoted swinging links 18 which are bent at 19 and provided with threaded eyes for the reception of screw bolts 20 with manipulating handles 21. The outer face of the flange 15 is provided with a liquid-tight packing 22 fitting in a dovetailed groove and extending around the sides and bottom of the tank in position to bear against the swinging end or door 23 when the latter is thrown upward in position to close the end of the tank. Suitable hinges 24 are provided to support the tank end when in open position and an eye 25 is mounted upon the free edge thereof to which a rope or other means for manipulating the tank end may be secured. The latter corresponds in shape and size to the perimeter of the flange 15 and is likewise and coincidentally notched to permit the links to swing into proper position as shown in Figs. 6 and 7 and when the door is in position to close the end of the tank said links are swung inwardly and the screw bolts tightened to bear against the door and hold it in liquid-tight engagement with the packing above described.

The means for excavating the solid product from the tank will now be described but it may be stated as a preliminary to such description that if desired a number of tanks B may be employed in connection with a single excavating apparatus in which event the latter is mounted on a pair of tracks 26-26 arranged upon opposite sides of the series of tanks in position to guide the excavating apparatus from one tank to the other (see Figs. 2 and 4). Upon the tracks 26-26 is mounted a carriage comprising longitudinal beams 27-27 and cross beams 28-28 provided with wheels 29-29 for engaging said rails and with tracks 30-30 upon the upper faces of the beams 27, and at right angles to the first-named tracks upon which the bogie 31 is designed to travel. The frame of the bogie consists of parallel side beams 31-31, an intermediate beam 32 parallel therewith and end beams 33-34 (see Figs. 3 and 4). From said bogie depends an open V- or wedge-shaped frame 35 which is secured to the side beams and supports an endless belt carrying excavator bucket for removing the matter from the tank. The frame 35 comprises two end frames each of which comprises a pair of converging angle irons 36-36 secured at their upper ends to the side beams of the bogie and connected at their bottoms by a horizontal member 37, the end frames being rigidly connected together by cross braces 38-39. A shaft 40 is

journalized at its ends upon the horizontal members 37 and carries a pair of sprocket wheels 41-41 and shafts 42-43 each likewise carrying a pair of sprockets are mounted upon the under and upper sides respectively of the side beams 31 but spaced apart longitudinally of said beams. A pair of sprocket chains 44 is mounted upon the sprockets above referred to and carries a series of excavator buckets 45-45 having serrated cutting edges 46 (see Figs. 2, 3 and 4). A conveyer trough 47 extends transversely across the bogie beneath the upper run of the endless belt being secured to the under side of the side beams 31 in position to receive the matter dumped from the buckets as the latter round the sprockets on shaft 43. The conveyer trough contains an endless worm 48 and terminates at one end in a downwardly directed chute 49 which discharges into a stationary conveyer trough 50 mounted upon the side of the tank. The bogie is provided with means for driving the worm of the conveyer carried thereby and the excavator belt, being provided for this purpose with a motor 51, the shaft of which carries a pinion 52 meshing with a larger pinion 53 upon a countershaft 54. The latter also carries a pinion 55 which meshes with a pinion 56 upon the shaft 43 above mentioned which carries one of the pairs of sprocket wheels and drives the elevator belt. Upon the shaft 43 is also mounted a sprocket 57 which drives an endless chain 58 turning a sprocket 59 upon the shaft 60 of the conveyer worm or spiral.

In the construction just described, the motor mounted on the bogie drives both the excavator belt and the transverse conveyer. When one of the series of tanks above described is to be emptied the end door thereof is lowered, the carriage is propelled along its tracks 26 into registry with the tank and the bogie pushed or driven upon its tracks 30 until the excavating mechanism is in contact with the solid mass of lime soap. In the meantime, or before moving the bogie, the electric motor is started so that when the mechanism is brought into contact with the soap the excavator buckets, which preferably are of a length to extend entirely across the interior of the tank, rise along the end wall and cut or shave off quantities thereof of the mass of soap which, falling into the buckets, is carried up and dumped into the transverse conveyer 57 and by the latter transferred to the longitudinal stationary conveyer trough 50. The excavating apparatus is of course fed forward as the buckets remove the soap until substantially the entire mass has been removed.

The trough 50 also contains a conveyer worm 61 driven by any suitable means as by the belt pulley 62 (see Fig. 4) and discharges at its end into a stationary trans-

verse conveyer trough 63 having a worm 64 driven by a belt pulley 65. From the last named conveyer the material is discharged into a grinding mill 66 of any suitable character driven by a belt pulley 67, and from said mill the ground soap is discharged by a chute 68 into the boot of an elevator 70. The latter preferably comprises the ordinary pair of endless chains 71 driven by a belt pulley 72 and series of buckets 73 connected across the chains which discharge into a chute 74 arranged beneath the upper end of the elevator. Chute 74 dumps the material into a conveyer 75 which extends from said chute across an extraction tower 76 to a soap kettle 77. The last named conveyer is likewise provided with a worm 78 driven by a pulley 79 and discharges at its farther end 80 into said soap kettle, but intermediate its ends and above the tower 76 is a trap or door 81 which may be opened for discharging the material received by said conveyer into the tower or closed to permit the material to pass on to the soap kettle. The first treatment that the ground soap receives after leaving the mill 66 is a washing in the tower 76 and therefore the trap 81 is left open when material is being conveyed from the mill so that the tower is filled to the desired depth with granulated lime soap. At its lower end the tower is provided with a cock controlled draw-off pipe 82 and above the bottom with a false or perforated bottom 83 which supports the column of material while it is being sprayed with water from the spray 84 for the purpose of washing out the glycerin contained in the soap. When the washing operation is completed the sweet water is drawn off to a suitable storage reservoir through the pipe 82 and the door 84 may be opened for the purpose of shoveling out the granulated soap into the chute 85 by which it is returned to the boot of the elevator. Before the material is again raised and dumped into the conveyer 75, however, the trap 81 therein is closed so that the material is then fed across the tower and discharged into the soap kettle 77. In the latter the lime soap is treated with carbonate of soda or potash, according to the nature of the soap desired, preferably in a salt solution whereby the lime soap is converted into soda or potash soap, as the case may be, and the lime deposited as mud at the bottom of the kettle. After the material is allowed to stand sufficiently long, the soap rises to the top, leaving a clear salt solution between the lime mud on the bottom and the soap, which solution together with the mud is drawn off into a tank 86 where the mud is allowed to settle. The supernatant lye is then pumped out and the mud forced by the pump 87 into a filter press 88 by which the remaining liquid is extracted therefrom. If the liquid

remaining in the mud at this point is not of sufficient value, the mud may be disposed of without the filter press operation.

By the use of the apparatus above described the soap-making operation may be conducted substantially continuously with the minimum handling, it only being necessary for the product to be removed by manual means from the tower 76, the rest of the operation being automatic except in so far as it is necessary for the operator to intervene to open and close valves, etc., to properly control and direct the material.

I claim:

1. In an apparatus for the manufacture of soap and the like, a mixing tank, a reaction tank, a stirrer in the former, means for excavating the solid material from the latter, and a pipe connection by which the liquid may be drawn from the stirrer tank to the reaction tank. 80

2. In an apparatus for making soap, a stirrer tank, a reaction tank and a grinding mill, a pipe connecting the stirrer tank and the reaction tank, and means for excavating the solid material from the reaction tank 90 and transferring it to the mill.

3. In an apparatus of the class described, an extraction tower, a soap kettle, a conveyer adapted to discharge at will into either the extraction tower or the soap kettle, and means for depositing granulated material in said conveyer. 95

4. In an apparatus of the class described, an extraction tank, a soap kettle, a conveyer extending across said extraction tank and to said soap kettle, and a trap in the conveyer by which material deposited therein may be discharged into the extraction tower when desired. 100

5. In apparatus of the class described, an extraction tower, a soap kettle, a conveyer extending over the extraction tower and communicating with the soap kettle, a trap in said conveyer adapted to discharge material therefrom into the extraction tower, an elevator adapted to discharge material into said conveyer, and a chute adapted to discharge material taken from said tower into the boot of the elevator. 110

6. In an apparatus of the class described, a soap kettle, a tank, means for discharging material from the soap kettle into the tank, a pump, a filter press and connections whereby material contained in the soap kettle may be discharged into the tank and the contents of the tank may be pumped into the filter press. 120

7. In apparatus of the class described, a mixing tank A, a reaction tank B, a pipe connecting the two for discharging the contents of the mixing tank into the reaction tank, a grinding mill 66, means for excavating solid material from the reaction tank and discharging it into the mill, an extrac- 125

130

- tion tower, a soap kettle, a conveyer adapted to discharge at will into either the extraction tower or the soap kettle, an elevator adapted to convey material discharged
- 5 from the mill into said conveyer, a tank, means for discharging the contents of the soap kettle into the tank, a filter press, a

pump and connections whereby the pump may discharge material from the last named tank into the filter press.

PETER KREBITZ.
